Application September 1, 1934, Serial No. 742,382

52 Claims.

(CL. 1—3)

The present invention is concerned with stapling and more particularly relates to stapling machines of the character sustaining a strip of staples and having means for advancing a single 5 staple of the strip in vertical registration or alignment with a race or raceway in which a single staple is guided and progressively moved downwardly by a blade of a reciprocable driver to permit the legs of the guided staple to first 10 penetrate several papers and/or cardboard sheets or the like after which the legs of the guided staple are swung by the aid of a cooperating anvil as to be disposed against the lowermost surface of the bottom sheet for properly 15 fastening or clinching several sheets of paper and/or cardboard together.

A serious problem in the stapling machine art and vitally concerning the proper operation of a stapling machine has to do with undesirable and inherent clogging of the machine, that is, as a 20 result of clogging due to many causes the reciprocable driver becomes jammed or locked preventing its proper operation. With this condition at hand, the stapling machine was generally 25 sent back to the factory where it was disassembled, inspected, the fault corrected and finally sent back to the owner. The causes of clogging 30 may be chiefly enumerated as follows: first,—clogging due to accumulation of glue from the film of adhesive on a staple strip, the glue collecting in the form of wads in the staple race at 35 positions where the foremost staple of the strip enters. With the race partly obstructed due to the accumulation of wads of glue, the next successive staple of the strip advanced forwardly but irregularly as to overhang or in part register 40 with the race. Consequently on the next downward stroke of the driver the overhanging staple caused the blade of the driver to jam or lock, thus preventing completion of the downward stroke of the driver or the retraction thereof.

Second, another cause of clogging of a staple or parts thereof was due to tolerance, namely excessive and appreciable lateral shift of the 45 legs and crowns of the staples of a strip of staples mounted on the supporting staple rail as well as the displacement of a staple in the staple guide race, the lateral shifting of the staples of a strip relative to the rail slightly offset the line of the 50 travel of the staple strip towards the race and further caused improper registration of a staple in respect to the race such that when the blade of the driver struck the misaligned staple in the race, it was impossible to complete the downward stroke 55 without cutting or shearing the staple into pieces.

Pursuant to cutting or shearing of a staple, the cut or chipped pieces thereof would collect in the race and prevent further proper staple feed thereto, thus further misaligning the staples disposed in back of the race. Accordingly the 5 staples at the back of the race would pile up on the supporting rail, causing slight angular displacement of the staple strip relative to the rail, and hence the staples of the strip are severally advanced as to partly overlap or partly register 10 with the race preparatory to downward stroke of the driver in which case only fragmentary parts of successively fed staples would fall into the race after the operation of the driver.

Third, clogging was also carried into effect by 15 snapping the follower block several times against the rear end of the strip of staples. This action broke and damaged the adhesive film of the staple strip causing parts of the latter to telescope on the guide rail so that length of the 20 staple strip decreased concomitantly increasing the width of several of the staples in the strip guide channel, which increase in widths caused spreading of the legs of several of the staples. With several of the staples thus deformed such 25 that the legs thereof were needlessly diverged, the sides of the staples frictionally bear against the walls of the strip guide channel bringing about improper feed of a staple of the strip to the vertical race and as in the case of accumulation 30 of wads of glue, improper registration of a staple relative to the race was obtained. Therefore, only a part of a staple was severed by the blade of the driver, hence chips of staples or parts thereof would accumulate in the race and 35 cause clogging.

Fourth, another cause of clogging was due to 40 the incompleteness of the downward stroke of the driver after the blade thereof has severed a staple from the strip, thus leaving the disconnected staple in the race so that a successive staple parted from the strip could not register properly 45 with the race or would enter the race in part or staples within the race or cut parts of staples would accumulate to prevent a complete or full downward stroke of the driver.

Fifth, clogging may also be brought about by 50 reason of inherent defects in the staple strip. If poorly manufactured or inaccurately made, the strip could not be properly confined in the strip guide channel. In such case, portions of the strip would telescope under the influence of the normal pressure on the follower exerted by the spring. Hence improper registration of a staple in respect to the race would be obtained and conse- 55

quently clogging would take place. This fault was due to inaccurately made staples. One staple of a strip may be wrong. Or the entire strip may be defective. In either case improper feed of a 5 staple in respect to the race would take place as a staple or strip of staples could not properly be confined within the strip guide channel before reaching the race.

The invention has as an important object the 10 provision of a novel stapling machine having positive means to prevent clogging which would take place if wads of glue were permitted to accumulate by cleaning the staple raceway of glue on each complete stroke or cycle of the driver.

15 The invention comprehends as another object the provision of means to prevent clogging normally due to tolerance by closely confining the staple strip within the guide channel of the pivoted arm of the stapling machine as the foremost 20 staple is advanced towards the vertical race and by also closely confining a properly registered staple within the staple race. In this way the strip of staples in the guide channel and a staple in the 25 staple race cannot be accidentally displaced in any plane. In other words, according to the invention, means to prevent accidental displacement of a staple strip in the guide channel and a staple in a race is prevented by the provision of a strip guide channel and a race having a precision fit relative to the staple strip and a staple 30 respectively. With a staple strip closely confined within the strip guide channel and a staple closely confined in the race, the staple strip and/or a staple are prevented from accidental displacement 35 in any plane.

The invention has as a specific and important object to provide means to prevent clogging due to the snapping of the follower in the provision of means causing the follower block to hurdle 40 or jump the strip of staples provided the spring to which the follower block is connected be extended and released, the blow or impact of the follower block being absorbed by a jacket or housing attached to the frame of the stapling machine, instead as in the case of older types of 45 stapling machines, if the follower block were snapped, the force developed pursuant to the release of the spring, was absorbed directly by the rear portion of the staple strip, causing parts 50 thereof to telescope in the guide channel ultimately bringing about improper registration of a staple in respect to the race and such a condition as previously pointed out causes clogging.

Another important object of the invention 55 resides in the provision of a novel stroke control mechanism to prevent a complete upward stroke of the driver until a complete downward stroke thereof has been made.

The invention has as a further object the provision of a composite staple strip supporting track 60 comprising a die cast zinc core on which is mounted a channeled rail of hardened steel, the outer surfaces of the rail having a relatively smooth finish formed by grinding or burnishing, 65 the side and the top surfaces of the rail meeting in relatively sharp corner edges, the outer rectilinear surfaces of the rail being adapted to faithfully guide a strip of staples in the guide channel of the frame.

70 The invention further comprehends as an object thereof to provide a staple expelling instrumentality or driver having a floating or loosely pivoted blade which is self aligning in respect to the raceway without causing undue friction with 75 the walls of the latter.

The invention has as a further object the provision of an improved stapling machine comprising an inner complementary race block having a durable and relatively rugged integrally connected spacer for holding the sides of the frame a required distance apart, the spacer being prevented from shifting downwardly under the impact of the driver on downward strokes thereof in the matter of discharging a staple or pieces of a staple from the raceway, and since the spacer is prevented from being displaced by the driver, the staple ejecting gap which is the foremost part of the strip guide channel is maintained constant, the gap being formed by the upper surface of the staple supporting rail and the lower surface of the spacer of the complementary race block.

The invention has as a further object the provision of an oscillatable trigger having a terminal portion thereof adapted to sustain a staple received in the raceway and having an intermediate portion adapted to clear a pocket or recess in back of the raceway of any chips or pieces of staples collected therein in the event and pursuant to incomplete registration of a staple relative to the race is obtained whereby the driver cuts a staple fed into the raceway into several parts.

The invention has as another object the provision of means to prevent undue friction or pinching of the driving blade in respect to the walls of the raceway comprising a self retractable staple supporting trigger having a loose pivotal connection permitting displacement thereof in several planes whereby upon downward displacement of the driving blade, the trigger is merely pivoted whereby the forward portion thereof is moved in an arcuate path only and downwardly and rearwardly throughout the downward movement of said forward portion and whereby said blade on further downward displacement frees said forward portion permitting the latter to be disposed against a rear face of said blade whereupon cocked spring means cooperates with the trigger to displace said trigger bodily, rearwardly, concomitantly, automatically, elevating said forward portion in back of said blade to yieldingly bear against said rear face.

The novel features characterizing the invention are set forth in the appended claims. However, it is to be understood, that the invention, both as to its organization and method of operation, together with other objects, advantages, and features thereof, may be best understood if considered in the light of the following description of a specific embodiment when read in connection with the accompanying drawings in which:

Fig. 1 is a longitudinal and vertical sectional view of a stapling machine according to the invention.

Fig. 2 is a sectional view on the line 2—2 of Fig. 1.

Fig. 3 is a sectional view on the line 3—3 of Fig. 1.

Fig. 4 is a disassembled or exploded view in perspective of several parts of the stapling machine 65 illustrated in Fig. 1.

Fig. 5 is a horizontal view taken on the line 5—5 of Fig. 1.

Fig. 6 is a section on the line 6—6 of Fig. 1.

Fig. 7 is a sectional view on the line 7—7 of Fig. 6 but illustrating the plunger or driver moving downwardly, the down stroke being incomplete. This view also illustrates partly in section the stroke control mechanism.

Fig. 8 is a view similar to Fig. 7 showing the 75

driver in position after having completed the down stroke.

Fig. 9 is a view substantially similar to Fig. 8 illustrating the plunger on the way up during the return stroke thereof.

Fig. 10 is a view similar to Fig. 7 illustrating the plunger on the way up during the return stroke thereof, the plunger previously having rear complementary race block.

10 Fig. 11 is a fragmentary transverse view partly in section of the swingable arm but more particularly illustrating in elevation a front view of the rear complementary race block.

15 Fig. 12 is a sectional view on the line 12-12 of Fig. 11 and

15 Fig. 13 is a bottom view of Fig. 11 along the line 13-13 thereof.

Referring to the drawings, the stapling machine is generally denoted 10. This machine 20 comprises an elongated base 11 to which is pivotally connected the displaceable arm 12 having a reciprocable driver or plunger broadly denoted 13.

25 The base comprises a top wall 13' having integrally depending sides 14 which are interconnected by a rear wall 15 integrally depending from the rear portion of the top wall 13'. Extending outwardly and downwardly at the front portion of top wall 13' but integral therewith is the sloping wall 16. Rear wall 15 and the spaced sides 14 together with sloping wall 16 constitute a rim in which resilient or appropriate rubber pads 17 and 18 are suitably secured. More specifically the rear pad 17 is disposed as to be held against the rear wall 15 by spaced prongs 18' of an offset plate 19 disconnectably secured by a set screw 20 to the lower wall 21 of a channeled shaped member generally denoted 22 having its upstanding arms 23 and 24 passed through suitable slots 25 in the top wall 13' of the base. The shank of set screw 20 also passes into a suitable opening in the top wall 13' to hold the lower wall 21 of the channel thereagainst. Suitable rivets or the like 26 also secure the top plate 13' and the lower wall 21 of the channel 22 together.

50 The arms 23 and 24 extend above the base, constitute perforated but elongated ears or lugs adapted to movably guide the displacement of the swingable arm 12, ears 23 and 24 being adapted to sustain the transversely disposed fulcrum rod 27 on which the arm 12 is pivoted.

55 Resilient pad 18 is secured against the inner surface of the forwardly disposed inclined wall 16 of the base by prong 28 carried by an offset plate 29 secured to a lower depressed wall 30 by set screw 31. It will be noted that pads 17 and 18 extend below the rim of the base and constitute resilient seats to prevent injuring or marring of a supporting surface on which the stapling machine is placed.

60 The depressed wall 30 of the base constitutes a transversely disposed shallow recess in which an anvil plate 33 is appropriately retained. The anvil plate is provided with suitable indentations 34 for properly folding the legs 35 of a staple 36 of a unitary staple strip generally denoted 37.

65 The swingable arm 12 comprises a composite track broadly denoted 38 embodying core 39 and the channeled rail 40. The core 39 is a zinc die casting so formed as to have an elongated body having longitudinal sides 42 and 43 rabbeted to provide grooves 44 defining laterally disposed shoulders 45 and spaced vertical rectilinear faces as 46 which are perpendicular to shoulders 45.

70 75 The top horizontal surface 47 of the core is rela-

tively smooth and is perpendicular to the vertical faces 46. The longitudinal central portion of the core defined by the vertical surfaces 46 and horizontal surface 47 constitutes a reduced portion, the upper surface 47 of which forms a seat for the horizontal lower face 48 of web 49 of the channeled shaped rail 40. Depending sides 50 of the rail closely straddle and fit the smooth vertical faces 46 of the core. The inner horizontal face or surface 48 of the rail is perpendicular to the inner vertical faces 51 of the depending sides 50. Hence it is apparent that transverse play of the rail relative to the core cannot take place. Longitudinal displacement of the rail in respect to the core is also prevented. To this end the reduced portion of the rail is provided with transverse openings 52 which register with the transversely aligned openings as 53 in the spaced sides 50 of the rail. A suitable pin or rivet (not shown) is passed through the registered openings 52 and 53 after the rail is placed on the reduced portion of the core. The rivets subsequently have their ends upset as to be flush with the vertical outer faces of the sides 50 of the rail.

25 The upper surface 54 of the rail is parallel to the inside horizontal surface 48 and the outer vertical surfaces 55 and 56 are perpendicular to upper surface 54, the latter and outer surfaces 55 and 56 meeting to define relatively sharp edges as 57. The rail is preferably made of hardened steel having internally and externally accurately ground or burnished precision surfaces, the outside surfaces 54, 55 and 56 forming complementary means for faithfully aiding to guide the staple strip 37 as it is intermittently advanced forwardly.

30 Appropriately attached to the vertical sides of the core is a frame generally designated 58. The frame includes spaced sides 59 and 60 each provided with upstanding vertically disposed wings as 61 having spaced openings 62 and 63 at the lower portions thereof to frictionally receive the laterally extending spaced tongues 64 and 65 of a transverse spacer 66 of an inner complementary race block broadly denoted 67. Pins or rivets as 68 extending transversely of the core are received in companion aligned openings as 69 and 70 of the core and sides of the frame after which their outer ends are slightly upset for holding 50 the sides of the frame against the sides of the core as is well understood.

35 The complementary race block 67 is provided with an integrally depending vertically disposed plate 71 having forwardly extending marginal ledges 72 and 73 comprising forwardly and vertically disposed outer surfaces as 74 out of alignment but parallel to the front vertical face 75 of depending plate 71.

40 With the frame mounted on and secured to the core of the track, the reduced part 76 of the depending plate 71 abuts the end faces 77 of the core 39 and the rear vertical faces 78 of the ledges 72 and 73 abut the end vertical and flat faces as 79 of sides of the frame (see Figs. 13).

45 Depending plate 71 has a centrally disposed reduced but externally squared portion 80 on which the forward end 81 of the rail 40 is mounted, the forwardly disposed vertical end surface of the rail being flush or in the same plane with vertical front face 75 of the depending plate 71.

50 The horizontal spacer 66 embodies a forwardly extending horizontal lip 82 having its lower horizontal surface spaced from the top surface 54 of the rail as to leave a relatively narrow trans-

versely disposed but horizontal staple ejecting gap 82' just slightly larger than the thickness of the staple.

Sides 59 and 60 of the frame respectively, each 5 embody inwardly extending overhanging flanges 83 and 84 having their lower faces as 85 parallel to the horizontal upper surfaces 54 of rail 40 and each of the sides 59 and 60 further includes an inwardly and longitudinally disposed rib 86 having a vertically arranged inner face 87 adapted to slidably guide and closely confine the vertical legs 35 of a staple on the rail.

The inner faces of the frame and the outer surfaces 54, 55 and 56 of the rail form an elongated channel 88 in which a staple strip 37 is slidably guided, and since the ribbed sides of the frame are disposed in close spatial proximity to the legs of the staples the latter accordingly are closely confined in the strip guide channel 88 20 until a staple thereof is ejected through gap 82', the latter being in alignment and in communication with the staple strip channel 88 and is the forward portion thereof. The clearance between the legs of a staple strip and adjacent ribs of the 25 sides of the frame is about the thickness of a sheet of paper, to wit, three to four thousandths of an inch. Hence the tolerance is negligible. It may be said therefore that in so far as the staple strip guide channel is concerned the staples 30 therein are supported with precision and without tolerance. In other words, the staple strip is moved in one plane along the guide rail.

The inside faces as 89 of ledges 72 and 73 are disposed in front of the forward face 15 of the 35 relatively rugged and durable complementary race block 67 and together with face 75 constitute the sides and rear face respectively of the vertically disposed staple race or raceway 90.

The inner forward face of the race 90 is 40 formed by the inwardly disposed vertical face or surface 91 of a rugged and durable complementary race block, namely, a U-shaped guard or shoe 92 having its spaced wings or sides 93 and 94 disposed rearwardly. When the guard 92 is 45 mounted on the forward portions of the sides of the frame, the walls of notches 95 of wings 93 and 94 straddle outwardly projecting correspondingly shaped lugs 96 carried by the sides of the frame and inwardly pressed lugs or stops 97 of 50 wings 93 and 94 are removably receivable in a recess as 98 of the spaced sides of the frame.

The raceway 90, thus formed by face 15 of the complementary race block 67 and the spaced faces 89 of spaced ledges thereof together with 55 the inside face 91 of the complementary race block 92 is in one plane at right angles to the strip guide channel 88 and in communication therewith, the faces of the race closely confining a staple in one plane.

60 A vertical post 99 is carried by the spacer 66. About post 99 is encircled a helicoidal spring 100. Surrounding the latter is a hollow housing 101 of driver or plunger 13, the housing being self retractable by reason of automatic expansion of 65 the spring.

Suitably secured to the upper part of the housing 101 is a relatively wide manipulating member or a curved cap 102 which includes a centrally arranged annular flange 103 about which 70 the upper end of the spring is appropriately anchored. As shown the housing has rectangular cross section.

The front wall of the housing carries a relatively thin but rectangular shaped blade 104 75 secured to the front wall. More specifically the frame is a casing, generally denoted 110. The

upper end of the blade includes an opening loosely arranged about neck 105 of rivet 106 which is fixedly secured to the front wall of the housing. By reason of the slight loose connection of the blade relative to the housing, the blade is self alining, pivoting about the neck 105 which serves as fulcrum means. The loose connection may be considered as a floating relation of the blade relative to the housing. In moving downwardly 10 the lower portion of the blade before entering into the raceway 90 is slidably guided between squared shoulders 107 of the upper portion or rim of guard 92 which extends above the elevation of spacer 66. In other words, when the plunger is fully retracted the lower portion of the blade is guided between the shoulders 107 and between the inner transverse face of the guard 92, and front face of the lip 82, the front face of lip 82 being in the same plane as the rearward face 15 of the raceway 90. In this position, the lower edge of the blade 104 is normally just slightly above the upper edge of the blade ejecting gap (see Fig. 11), thus permitting a staple to be fed into the raceway.

With the present construction, the raceway 25 closely confines a staple severed from the strip. Accordingly, the staple within the race cannot be accidentally shifted or misplaced out of the vertical plane by reason of the fact that the raceway is in one plane and by reason of the close 30 and slidably confinement of the staple, the walls of the raceway, in fact constituting a precision fit of a staple relative to the raceway. By reason of the precision fit, the driver, as previously pointed out, causes a complete discharge of any stray 35 glue from the raceway on each cycle thereof, thereby successively and periodically cleaning the raceway of any glue that might collect and cause clogging.

The spacer 66 and depending plate 11 defining the complementary race block 67 are made from a relatively hard steel. The lower horizontal surface of the spacer and the lower horizontal faces of the inwardly disposed flanges 83 and 84 overhanging the sides of the frame are in alinement 45 to provide a continuous plane to guide the tops or crowns of the staple strip.

Hitherto, in stapling machines of the character referred to, one cause of clogging was due to improper registration of a staple with the raceway 50 by reason of the downward shifting or displacement of the race block as a result of being subjected to successive blows by the driver when operated for chopping up a staple or part thereof in the raceway or shifting due to the usual operation of the machine. According to the invention this objection is overcome and shifting or displacement is prevented by making the spacer of the rugged race block 67 integral with its depending plate 11 which forms a complementary part of the raceway. By preventing downward displacement or shifting of the race block due to downward pressure of the driver against spacer 66, the staple ejecting gap 82' between guide rail and lip 82 is held constant, 65 that is to say although the lower portion of housing 101 of the driver 13 may transmit successive impacts against the spacer 66 which serves as a stop for the housing when downwardly displaced, the complementary race block 67 according to the invention will not be displaced. This is an important feature of the invention.

Interposed between and suitably fixed or anchored to the spaced upstanding wings 61 of the frame is a casing, generally denoted 110. The

casing comprises a forwardly disposed upstanding channel 111 having rearwardly depending sides 112 and 113 which are inwardly offset defining spaced rearwardly extending wings 114 and 115 disposed spatially in respect to the spaced side wings 61 of the frame.

A pin 116 extending transversely of the casing 110 at the lower portion thereof has overhanging terminals receivable in aligned openings 117 in the spaced wings 61 of the frame. Pivotally carried by fulcrum pin 116 is a latch lock member 118 which is disposed at the rear of the vertical opening 119 in the front wall 111 of channel 110. A spring 120' having its intermediate portion coiled about transverse pin 116 has its lower terminal abutting spacer 66 and its upper terminal urged against an intermediate portion of the latch member 118. In other words, spring 120' normally urges the upper portion of the latch member in a direction towards opening 119.

To facilitate understanding of the operation of the stroke control mechanism, it is important to keep in mind the position of the stop lug 120 which is carried by housing 101 and overhangs the rear wall 121 thereof. When the reciprocable driver is fully retracted by spring 100 (see Fig. 1) the upper face 122 of the stop lug 120 is against the upper face 123 of the slot 119, that is, by reason of the coaction of stop lug or overhanging means 120 with the slot 119, the upward stroke of the driver is limited.

In this normal position of the stop lug 120, the forwardly disposed lateral lip 124 of the latch member 118 bears against the rear face of stop lug 120. In other words, the lip of the latch member is clear of the rectangular slot 119. If, however, the plunger is depressed, slightly or downwardly, failing to complete a full down stroke, lip 124 of the latch member automatically enters or falls into slot or opening 119 by the automatic action of spring 120'. Consequently, if the plunger is released, in the event a full down stroke has not been consummated, stop lug 120, now bears against the lower face of the lateral lip 124, the latter serving as intervening means to prevent complete retraction of the driver when a full down stroke has not been effected.

It follows therefore that it is necessary to make a complete down stroke of the plunger before a complete return stroke can be made. Consequently if no complete return stroke has been made, the lower part of the driving blade 104 remains within the raceway 90, acting as a closure for the staple ejecting gap 82' to prevent a successive staple of the staple strip to enter the raceway. Hence with the present invention, only one staple may be admitted into the raceway at one time. It follows that a staple within the raceway must be ejected before a successive staple may be admitted therein. This is an important feature of the invention.

In completing the full down stroke of the driver, the lateral lip 124 goes through the following cycle; first; it is normally out of the opening 119 (Fig. 1); secondly; when the plunger is moved down it automatically enters opening 119 and acts as an intervener, for example, see Figs. 8 and 10; thirdly, during the continuation of the down stroke the intervening portion 125 of the rear wall 121 between lower and upper openings 126 and 127 of the driver housing (see Fig. 7) actuates the wheel or pawl 128 by first abutting intermediate cam or finger 131 causing

the pawl to rotate or oscillate slightly causing a finger or cam 129 to abut an intermediate portion of latch member 118; fourthly, this action retracts the lip 124 from the opening 119, the pawl being rotatably mounted and guided on the transverse pin 130 carried by side walls 112 and 113 of the casing 110.

Fifthly, when the down stroke has been completed (see Fig. 8) the intervening portion 125 clears, or is free of the pawl 128 and its intermediate nose or finger 131 falls into the upper opening 127 and consequently by reason of the inherent action of spring 120', lip 124 again falls into opening 119. In this position of the driver, the housing 101 is against the spacer 66 of the complementary race block 67 the spacer in this instance serving as a stop.

Sixthly, when the plunger is retracted, opening 127 moves upwardly and away from the pawl 128 but the intervening portion 125 oscillates or rocks the pawl, rotating it in opposite direction, hence cam or finger 132 thereof strikes latch member 118 moving the latter rearwardly, again causing lip 124 to leave opening 119.

Finally, since the stop lug 120 has reached the upper portion of opening 119 at a time when the latch is withdrawn therefrom, at the completion of the upward stroke of the driver, the stop lug abuts the upper face of opening 119. However, at this time the intermediate finger or cam 131 falls into the lower opening or pocket 126, which action permits the latch member to rotate the pawl in an opposite direction by reason of the pressure on the part of spring 120', and the forward portion of lip 124 moves towards opening 119 but cannot enter therein since the stop lug 120 is now occupying the upper end of opening 119 (see Fig. 1). It is therefore apparent that if a complete downward stroke has been made, the plunger may be fully retracted. In other words, the latch member is clear of opening 119. Where an incomplete down stroke has been made, it is impossible to carry into effect a complete return stroke by reason of disposition of the lip of the latch member, which lip is automatically arranged in opening 119 and serves as an intervener as previously pointed out. The stroke control mechanism above alluded to is an important feature of the present invention.

With the old form of stapling machines, should the operator make several incomplete strokes, staples would be fed into the raceway but not discharged therefrom, obviously causing an accumulation of bent and deformed staples within the raceway. The staples accumulated spread and would wedge together and thereby become tightly lodged in the raceway ultimately causing wedging of the driver in the raceway and preventing registration of successive staples. Due to clogging of the raceway and wedging of the blade of the driver, the driver becomes locked preventing any displacement thereof. With the present invention this difficulty is overcome for if a staple is not completely discharged by a full stroke of the driver, the stroke control mechanism preventing a complete upward stroke thereby closing entrance to the raceway, and hence the driving blade of the driver according to the invention, does not rise high enough to clear the foremost staple of the staple strip thereby preventing a successive staple from entering the raceway. Consequently a full down stroke is necessary to expel the staple in the raceway. In other words, according to the invention means is provided to prevent entrance of a staple in the

raceway if there be a staple in part or in whole within the raceway.

Associated with core 39 and pivotally sustained by a transverse fulcrum pin or supporting means 5 135 carried thereby is an oscillatable trigger or lever generally designated 136. The body of the trigger is provided with a relatively short longitudinally disposed slot 137 forming a loose pivotal connection with pin 135 to permit slight 10 longitudinal displacement of the trigger after the latter has been depressed or released. The trigger has its intermediate portion 138 slidably disposed and guided in a reduced longitudinal slot 139 axially disposed in the core and its for- 15 wardly disposed portion 140 arranged to travel in the vertical rectangular shaped enlarged opening or pocket 141 which is centrally located in the core and is in communication with reduced slot 139, the latter terminating in a vertical recess 20 142 in which the upper portion of the frustro-conical spring 143 is secured. The lower portion of spring 143 is coiled about post 144 carried by the rear terminal 145 of the trigger. Spring 143 acts to hold the forward portion 140 of the trigger 25 normally elevated or raised. The terminal 146 of the forward portion 140 of the trigger is held in a normally raised position by spring 143 and is guided in the vertical slot 147 in the depending plate 71. The terminal portion 146 further 30 extends beyond the front face of depending plate 71 and projects into the vertical raceway (see Fig. 1) such that its foremost inclined extremity 148 is in close proximity to the forwardly disposed surface of the raceway, which is formed by inner 35 transverse face 91 of guide channel 92.

As illustrated in Fig. 1, the blade 104 is slightly above a staple 36 which is in registration with the staple raceway 90. Movement of the plunger downwardly, severs the registered staple from the 40 staple strip 37. The severed staple is moved downward within the raceway by the lower portion of the driving blade 104. The crown of the staple, accordingly meets the overhanging portion of the trigger. Further downward movement of 45 the driving blade causes the front portion of the trigger to pivot or swing downwardly and slightly inwardly relative to the core, that is although the staple is moved downwardly in one plane by reason of its close confinement in the 50 raceway, the terminal portion of the trigger disappears due to the latter's pivotal relation with supporting pin 135 and is confined within vertical slot 147 and accordingly is clear of the staple in the raceway. Continued further movement of 55 the driving blade downwardly causes the legs of the downwardly moving staple to strike the indentations 34 of the anvil 33 carried by the base. The staple accordingly is deformed and expelled from the raceway.

60 Immediately after the lower portion of the driving blade has passed the terminal of the trigger which is now disposed in the vertical slot 147, the trigger automatically is restored to a raised position by reason of spring 143. That is to say, although the driving blade is still moving down, the forward portion of the trigger is elevated but bears yieldingly against the downwardly moving blade. (see Fig. 8), by reason of the loose pivotal connection, permitting slight 65 longitudinal rearward bodily displacement of the trigger but caused by the action of spring 143, and consequently undue friction or binding between the driving blade and the forward wall of the raceway is prevented.

70 75 Conical spring 143 is normally slightly dis-

torted, that is, its vertical axis is at an angle other than a right angle relative to the terminal and enlarged convolution 143' to provide a slight longitudinal component of force to permit the terminal of the trigger to normally overhang the raceway. A relatively great longitudinal component of force is needless and would cause undue friction of the trigger with the driving blade and pinching of the driving blade with the forward face of the raceway. Hence a relatively small longitudinal component is utilized and binding of the driving blade with the rear wall 10 of the raceway is prevented.

Recapitulating as the driving blade moves downwardly, the trigger first merely pivots on 15 pin 135 and when the forward terminal 146 thereof is clear of raceway 90, it slips off the bottom of the driving blade, at which time because of the larger vertical component of force of the cocked conical spring 143, the terminal of the trigger is raised before the return of the blade. This terminal is automatically elevated in back of the driving blade, the action of the cocked spring together with the loose pivotal connection of the trigger, causing the latter to move bodily rearwardly. The terminal of the trigger yieldingly bears against the rear side of the driving blade and thus awaits the return of the driver on the up stroke at which time the blade has reached above the elevation of the receded terminal consequently the trigger is bodily brought forwardly by the longitudinal component and thus the terminal of the trigger again overhangs the raceway to support a successive staple fed therein.

In the event, a staple has been cut into pieces by the driving blade, should improper registration of the staple with the raceway take place, cut pieces will fall into the spaced vertical slots 190 of the depending plate 71 and in back 40 thereof into the pocket or recess 141 defined by the forwardly disposed spaced terminals 191 of the core 39, these terminals having sloping faces 192 in which pieces of cut staples ride downwardly and into the pocket or throat 141 and onto the base of the machine. Accumulation of pieces of cut up staples in throat 141 is also prevented by the automatic return of the forward portion of the trigger and in striking upper face 193 of the vertical trigger guide slot 141, pieces 45 of staples clinging to the trigger are shaken off. Since the trigger during a complete cycle thereof travels through the major portion of opening 141, it also facilitates to keep the latter free of any small pieces of staples, causing the latter to fall 50 through opening or throat 141 and outside of the arm onto the base. Chips of staples failing to fall into throat 141 ride downwardly on the inclined faces or chutes 194 on plate 71 and will 55 be ejected from the raceway before a succeeding staple is admitted therein.

Suitable pressure is automatically provided at the back of the staple strip 37 to urge the foremost staple thereof towards the raceway. For this purpose a follower broadly denoted 150 is 60 slidably mounted on rail 40 as to abut the rear end of the staple strip. The follower block 150 is a channel shaped member as shown.

Rigidly secured to the follower is an elongated metal strap 151 which comprises a cam shaped 70 terminal 152 removably receivable in an elongated opening 153 of a saddle 154 having spaced upstanding perforated manipulatable ears 155.

Interconnecting the spaced ears 155 of saddle 75 154 is a transverse pin 156 which is loosely sur-

rounded by the curved eye portion of clip 157 having spaced arms 158 between which the rear end of a relatively wide but flat spring 159 is permanently secured, that is, the fulcrum pin 156 may be rotated relative to the eye portion of the clip if saddle 154 is tilted upwardly and forwardly. The eye portion of the clip may be considered as a bearing in which pin 156 is rotated if the saddle be tilted. The innermost end 160 of spring 159 is appropriately retained in the diametrically disposed slot 161 of the rotatable and adjustable arbor or bolt 162 journaled in the spaced wings 61 of the frame, the width of the spring 159 being substantially co-extensive the width of the transverse gap defined by the spaced wings 114 and 115 of stroke control mechanism housing 110.

One end of the arbor is provided with a suitable slot adapted to receive a tapered portion of a screw driver or the like whereby the arbor may be rotated to wind up the spring or adjust the tension thereof. With the desired pressure adjusted, a locking stud 164 is actuated so that its flanged head 165 is clamped against the enlarged head 166 of the arbor to hold the latter against displacement. By reason of the pressure applied to the cam 152 by the saddle 154, the follower block 150 urges the staple strip forwardly as is well understood.

30 If the saddle 154 be reciprocated one or more times accidentally or deliberately, the inner face of opening 153 rides over the outside rear face of cam 152 and the saddle 154 becomes detached from the cam, flying forwardly by the action of the spring, namely, hurdles or jumps the intermediate portion of the staple strip and strikes against the rearwardly disposed irregularly shaped transverse closure 167 disconnectably mounted on the spaced side wings as 168 of a jacket generally denoted 169. More specifically, the depending tongues 170 of the closure 167 absorb the impact of the flying saddle. In this way telescoping of the staple strip is prevented as a result of snapping of the follower block.

45 The closure 167 is provided with laterally disposed lugs 171 and recesses 172 which respectively cooperate and interlock with recesses 173 and lugs or tongues 174 of the channeled shaped jacket 169 to prevent bodily transverse displacement of the side wings 168 while the set screw 175 adjustably interconnected with the threaded boss 174 of the rear casing 110 prevents longitudinal displacement of the closure 167 relative to the wings 168 of the jacket 169.

55 The forwardly disposed portions 176 of wings 168 and the front wall 177 of jacket 169 together with the front wall 111 of casing 110 constitute a rectangularly shaped bore 178 within which the hollow housing 101 is reciprocably guided, 60 the helicoidal spring 100 normally holding the housing in a raised or elevated position such that the blade 104 carried thereby is above the staple ejecting gap 82' as illustrated in Fig. 1, provided of course a complete down stroke of the driver had been previously consummated.

70 The wings 168 of the jacket 169 are secured to the sides of the frame by suitable nuts 179 adjustably mounted on transverse pin 180 passing transversely through the spaced sides of the frame and the core of the staple supporting track.

The jacket 169 has its lower portion cut away to provide reentrant recesses each having a longitudinal shoulder 181 cooperating with and seated on the top aligned surfaces 182, 183 and

184 of the complementary guide block or guard 92 to hold the latter against vertical displacement.

Closely embracing the outer vertical faces of the guard 92 and the front portions 176 of the wings of the jacket 169 is a channel shaped shield 185, the sides of which are secured to the front portions 176 by suitable means, such as adjustable bolts 186. The shield 185 aids also to prevent displacement of the complementary race block 92 relative to the companion complementary race block 61.

A latch 200 is swingably mounted on post 201 and is bodily carried by the pivotal arm 12. The free or lower end of the latch 200 includes a lip 202 to coat with a lower surface of web 21 of channel 22 about opening 203. As shown in Fig. 1, the swingable arm 12 is locked in an intermediate position by the latch 200. If it is desired to increase the gap between the forward portion of the arm and the anvil, the latch is manually displaced rearwardly, thus removing lip 202 from web 21. Spring 204 surrounding the latch then automatically operates to raise the arm which bodily carries the lower part of the latch partly through opening 203. By moving the forward portion of the arm downwardly, latch 200 automatically operates to dispose lip 202 against the lower face of the web 21 and hence the arm 12 is held in the intermediate position illustrated.

In the broader aspects of the invention, I do not desire to be understood as limiting the embodiment thereof to details herein shown illustratively as a wide variety of modifications may be made within the scope of the appended claims without departing from the spirit of the invention.

I claim:

1. In a stapling machine, the combination of, 40 a base having an anvil and a self-raising but compressible arm pivotally connected to said base, said arm comprising a reciprocable driver having a blade, said arm including a staple strip supporting rail, said arm comprising spaced sides 45 each having an inwardly disposed rib coaxing with depending legs of the staples of said strip to closely but movably confine said legs against the sides of said rail.

2. In a stapling machine, a base, an arm swingably connected thereto, a self retracting reciprocable driver movably guided within said arm, said arm comprising a composite track having a core embodying a squared reduced portion and a channeled rail immovably mounted on said core and on said reduced portion, complementary members defining a vertically disposed raceway, one of said members having spacer means including an integrally depending plate having forwardly disposed ledges, said plate having a 50 reduced squared portion on which one end of said rail is mounted, the other of said complementary members having means connected to a forward portion of said arm and comprising a transverse face disposed against the forward 55 faces of said ledges, said spacer means and rail defining a staple ejecting gap, said spacer means being adapted to receive the kinetic energy of said driver on downward displacement thereof and sustain adjacent horizontal faces of said 60 gap a predetermined distance apart.

3. In a stapling machine, the combination of, 70 a base, an arm pivotally associated with said base, said arm comprising a frame having spaced sides, complementary members defining a ver-

tically disposed raceway, one of said members comprising a transversely and horizontally disposed spacer interconnected with said sides, a vertically disposed plate integrally depending 5 from said spacer and having a squared and reduced central portion, and spaced forwardly disposed ledges, a composite track interposed between said sides and secured thereto, said track comprising a core having a reduced squared portion, a channeled rail immovably mounted on said core and having an end portion seated on said reduced portion of said plate, said core having a relatively large pocket disposed at the rear of said plate, a staple supporting trigger loosely 10 pivoted to said core and having a portion thereof disposed in said pocket and a terminal part extending through said plate and disposed to overhang the latter in said raceway, spring means cooperating with said trigger to normally hold 15 said terminal part elevated in said raceway, the other of said complementary members comprising a channeled body having sides connected to the sides of said frame and including transversely disposed surface means spaced from the forward 20 face of said plate and constituting the forward wall of said raceway.

4. In a stapling machine, the combination of, complementary members defining a vertically disposed raceway, one of said members comprising 30 spacer means having a depending integral plate including forwardly disposed squared ledges, said plate having a central reduced squared portion spaced from said ledges defining therewith openings to permit fragmentary portions of a staple 35 to fall in back of said plate, the other complementary member comprising a channeled body having transverse surface means disposed against the forward faces of said forwardly disposed ledges.

40 5. In a stapling machine, the combination of, complementary block members defining a vertically disposed raceway, one of said members comprising transverse spacer means and an integrally depending plate having a centrally disposed squared and reduced portion, a track having a rail mounted on said reduced portion, said spacer means having a forwardly disposed lip spaced from the upper surface of said rail to define therewith a staple ejecting gap, a trigger 45 pivotally sustained by said track and having a terminal normally projecting into said raceway, reciprocable driving means, said spacer means cooperating to absorb impacts from said driving means to prevent displacement of said 50 lip relative to said rail, said trigger having a loose pivotal connection for displacement thereof longitudinally and rearwardly relative to said track, said driving means having a self aligning blade guided in said raceway, said blade coacting 55 to displace the terminal portion of said trigger downwardly and rearwardly as to be free of said raceway, and means cooperating with said trigger to bodily rearwardly displace the latter and simultaneously elevate said terminal portion 60 preparatory to the retraction of said blade.

65 6. In a stapling machine, the combination of, a track having an opening, complementary members defining a vertically disposed raceway, a staple supporting trigger having a loose pivotal connection with said track and comprising a portion disposed in said opening and a free terminal, spring means cooperating with said trigger to permit said terminal to overhang said raceway, driving means having a blade guided in said raceway, said blade adapted on the downward dis-

placement thereof to disconnect a staple of a staple strip slidably guided on said track and move said staple downwardly and onto said terminal, said blade on further movement thereof in the same direction displacing said terminal in an arcuate path only throughout the downward movement of said terminal causing rearward displacement of said terminal, said terminal on continued downward displacement of said blade adapted to slip by and be free of said blade and be disposed at the rear thereof in yieldable contact therewith, said spring means acting to elevate said terminal when free of said blade, said spring means cooperating with said trigger and said terminal with the depressed 15 blade to bodily rearwardly displace said trigger relative to said raceway.

7. The stapling machine according to claim 6 characterized in that one of said complementary members comprises a horizontal spacer having a depending plate including means to permit a fragmentary portion of a staple to fall into said opening and shute means to permit a fragmentary portion of a staple to fall downwardly in said raceway.

8. In a stapling machine, the combination of, a base, an arm pivotally associated with said base, driving means reciprocally mounted on said arm, stroke control means associated with said driving means comprising an opening, a spring controlled pivoted latch member having terminal means normally disposed out of said opening, said driving means having overhanging means slidably relative to said opening and normally disposed at the upper portion of said opening upon the complete retraction of said driving means, said terminal entering said opening automatically upon downward displacement of said driving means, said terminal means constituting interventer means and in the path of travel of said overhanging means if said driving means be retracted before a full down stroke of the latter is completed.

9. The stapling machine according to claim 8 in which said stroke control means comprises mechanism for displacing said terminal means out of said opening in response to a complete downward stroke of said driving means.

10. The combination according to claim 8, in which said stroke control means comprises an oscillatable member actuated by said driving means to hold said latch member out of said opening.

11. In a stapling machine, the combination of, a frame having ribbed sides, a composite track secured to said sides, said track having a channeled staple strip supporting rail comprising relatively smooth outer side vertical faces and a common relatively smooth horizontal surface substantially perpendicular to said vertical faces, the latter and said surface constituting clearly defined longitudinally disposed edges, the ribs of said sides having vertical disposed faces coacting to closely but slidably confine portions of the legs of the staples of said strip against vertical faces of said rail.

12. In a stapling machine, the combination of, a base having an anvil and a self-raising but depressible arm pivotally connected to said base, said arm comprising a reciprocable driver, a blade pivotally connected to said driver and adapted to swing transversely in respect thereto, said arm including a staple strip supporting rail and comprising spaced sides each having an inwardly disposed rib coacting with depending legs of the

- staples of said strip to closely but movably confine said legs against the sides of said rail.
13. In a stapling machine, the combination of, means for closely but displaceably confining a staple strip in a longitudinally disposed channel substantially without tolerance, complementary members defining a raceway for closely but displaceably confining a staple of said strip substantially without tolerance, one of said members comprising horizontal spacer means having a depending plate, the other of said members comprising channel-shaped means, and self-aligning driving means for ejecting said staple from said raceway and constituting means disposed in part in the latter to prevent entrance of a successive staple in said raceway in the event said driving means has not been fully retracted.
14. In a stapling machine, the combination of, an arm having a longitudinally disposed channel in which a staple strip is movably guided and a transversely disposed raceway adapted to movably guide a staple of said strip, a follower slidably guided in said channel, said follower having a rearwardly extending cam, a tilttable saddle removably mounted on said cam and spring means connected to said saddle for urging said follower against said staple strip, said saddle upon reciprocation thereof being adapted to strike said cam and tilt said saddle whereby the rear portion of the latter coats to slip off said cam to be free thereof whereby said spring means automatically carries said saddle forwardly without contacting said staple strip.
15. In a stapling machine, the combination of, a track having an opening at the forward portion thereof, supporting means extending transversely of said opening, a trigger comprising a terminal and having an elongated opening loosely surrounding said supporting means, said elongated opening and supporting means comprising a loose connection, compressible spring means, reciprocable blade means for pivotally displacing said trigger to move said terminal to be free of said blade means on a downward stroke thereof, said trigger having a rear portion adapted to compress said spring means on downward displacement of said terminal, said spring means upon freeing of said terminal by said blade means automatically acting to elevate said terminal and concomitantly bodily rearwardly displace said trigger relative to said supporting means to dispose said terminal at the back of said blade means and yieldingly bear against the latter, said spring means expanding to bodily shift said trigger forwardly on retraction of said blade means at a time when the latter is bodily above said terminal.
16. In a stapling machine, the combination of, a track having a longitudinally disposed opening at the forward portion thereof, supporting means extending transversely of said opening, a trigger comprising a staple supporting terminal, and having an intermediately disposed elongated opening loosely surrounding said supporting means, means comprising a vertically disposed raceway, a blade reciprocably guided in the latter, spring means acting on said trigger to normally hold said terminal elevated upon complete retraction of said blade, said blade on downward displacement thereof causing pivotal displacement of said trigger to dispose said terminal clear of said raceway and out of the path of said blade, said spring means acting on said trigger to elevate said terminal and concomitantly rearwardly bodily displace said trigger relative to said supporting means during continued downward displacement of said blade with said terminal yieldingly in contact with said blade, said spring means cooperating to bodily displace said trigger forwardly and dispose said terminal in said raceway at a time when said blade is retracted and bodily above the elevation of said terminal.
17. In a stapling machine, the combination of, a pin, a staple supporting trigger having an elongated opening cooperating with said pin, depressible blade means for actuating said trigger, and spring means cooperating with said trigger to normally hold the forward portion thereof elevated and concomitantly bodily hold said trigger forwardly when said forward portion is free of said blade means, said spring means cooperating with said trigger and the latter with said blade means to bodily rearwardly displace said trigger in a depressed position of said blade means.
18. The combination according to claim 17 characterized in that said pin is transversely disposed and constitutes means to limit displacement of said trigger forwardly or rearwardly.
19. In a stapling machine, complementary members defining a vertically disposed raceway, one of said members comprising a rearwardly disposed horizontal spacer having a depending plate, the other complementary member comprising a channel-shaped body having transverse surface means spaced from the forward face of said plate.
20. In a stapling machine, the combination of, a base, an arm pivoted to said base, driving means reciprocably carried by said arm, stroke control means comprising an opening, a movable member disposed in said opening, and a spring controlled pivoted latch member normally disposed out of said opening, said driving means having overhanging means slideable relative to said opening and normally disposed at the upper portion of said opening upon the complete retraction of said driving means, said latch member entering said opening automatically upon initial downward displacement of said driving means, the latter having means to actuate said movable member and displace said latch member out of said opening on continued downward displacement of said driving means, said latch member constituting intervenor means in the path of the travel of said overhanging means if said driving means be retracted before a full down stroke of the latter is completed.
21. In a stapling machine, the combination of, a base, a swingable arm pivotally connected thereto, a self-retracting reciprocable driver, complementary members defining a vertically disposed raceway, one of said members comprising spacer means including a depending plate having an opening and shute means, said driver having a self-aligning blade slidably guided in said raceway, means for feeding a staple towards said raceway and in registration with the latter, said blade on the downward stroke of said driver adapted to eject said staple in registration with said raceway from the latter, said opening being adapted to receive and discharge a portion of a staple misaligned in said raceway and severed by said blade, said shute means being adapted to direct the travel of a portion of a staple within said raceway downwardly therein, and stroke control means to permit retraction of said blade but preventing a complete return stroke thereof to preclude admission of a successive staple of said strip in said raceway unless said driver has

completed a full down stroke pursuant to the entrance of a staple in part or in whole in said raceway.

22. In a stapling machine, the combination of, 5 a track for supporting a staple strip, a follower slidably mounted on said track, a rearwardly disposed extension carried by said follower, a spring, a saddle removably mounted on said extension, and a connection between said spring 10 and saddle to permit the latter to tilt and disengage from said extension upon appreciable impact of said saddle against said extension, said spring upon disengagement from said saddle causing the latter to fly forwardly.

15 23. In a stapling machine, the combination of, a track for slidably supporting a staple strip, a follower slidably mounted on said track and comprising a cam-shaped member, a spring, a saddle tiltable relative to said spring and removably 20 associated with said cam-shaped member, said spring causing said saddle to urge said follower against a rearward portion of said strip, said saddle upon extension and release of said spring coating to ride over said member as to be first 25 free thereof and subsequently hurdle a portion of said strip.

24. In a stapling machine, the combination of, a track for slidably supporting a staple strip, follower means mounted on said track and acting 30 against a rear end of said strip, an arcuate-shaped member carried by said follower means, spring means, a saddle removably mounted on said member, said saddle having a pivotal connection with said spring means, said saddle upon 35 extension and release of said spring means automatically pivoting to disengage itself from said member, said saddle upon disengagement thereof from said member hurdling a portion of said strip under the influence of said spring means.

40 25. In a stapling machine, the combination of, a track for supporting a staple strip, follower means mounted on said track and acting against a rear end of said strip, an extension carried by said follower means, spring means, and a saddle 45 removably engaging said extension, said saddle having a pivotal connection with said spring means, said saddle upon reciprocation thereof pivoting to disengage said extension and hurdle a portion of said staple strip.

50 26. In a stapling machine, the combination of, a slidable follower having a cam, a tiltable saddle removably engaging said follower, and spring means normally urging said saddle forwardly said saddle having a rear portion adapted to rise 55 upwardly and forwardly upon impact of said saddle against said cam whereby said saddle disengages from said cam as to be free thereof, said saddle upon disengagement hurdling forwardly under the influence of said spring means.

60 27. In a stapling machine, the combination of, a track for supporting a staple strip, a follower slidably mounted on said track and having a cam, spring means, and a tiltable saddle having a pivotal connection with said spring means and 65 having a perforated part removably engaging said cam under tension of said spring means, said saddle having a rear portion adapted to rise upwardly and forwardly upon impact of said saddle against said cam to effect disengagement of said 70 perforated part from said cam, said spring means automatically carrying said saddle forwardly without the latter contacting said strip upon disengagement of said part from said cam.

75 28. In a stapling machine, the combination of, a fulcrum pin, a staple supporting trigger hav-

ing a relatively elongated opening loosely surrounding said pin, spring means cooperating with said trigger to elevate the forward portion thereof and concomitantly bodily move said trigger forwardly, driving means having a slidably guided blade, said blade on downward displacement thereof coating to downwardly and rearwardly displace the forward portion of said trigger, said blade on further downward displacement freeing said forward portion permitting the latter to be disposed against a rear face of said blade, said spring means upon freeing of said trigger moving the latter rearwardly and concomitantly elevating said forward portion automatically in back of said blade.

10 29. In a stapling machine, the combination of, a fulcrum pin, a staple supporting trigger loosely and pivotally sustained by said pin, a cocked spring cooperating with said trigger to elevate the forward portion thereof and concomitantly bodily move said trigger forwardly, driving means having a slidably guided blade, said blade on downward displacement thereof coating to merely pivot said trigger whereby the forward portion of the latter is moved in an arcuate path only and downwardly and rearwardly throughout the downward movement of said forward portion, said blade on further downward displacement freeing said forward portion permitting the latter to be disposed against a rear face of said blade, said spring means upon freeing of said forward portion cooperating to displace said trigger bodily rearwardly concomitantly automatically elevating said forward portion in back of said blade to yieldingly bear against said rear face.

15 30. The combination according to claim 28 further characterized in that said fulcrum pin constitutes means to limit forward and rearward bodily displacement of said trigger.

20 31. The combination according to claim 28 in which said fulcrum pin constitutes means to limit forward and rearward bodily displacement of said trigger, and said forward portion when disposed in back of said blade being elevated prior to the retraction of said blade.

25 32. In a stapling machine, the combination of, a track having a longitudinally disposed opening at the forward portion thereof, supporting means extending transversely of said opening, a self elevating depressible blade, a trigger comprising a staple supporting terminal and having an elongated opening loosely surrounding said supporting means, spring means acting on said trigger to elevate said terminal and dispose the latter in the path of travel of said blade, the latter on downward displacement pivoting said trigger about said supporting means and causing said terminal to move downwardly and inwardly to be free of said blade, said spring means cooperating pursuant to the freeing of said terminal by said blade to bodily rearwardly move said trigger relative to said supporting means and concomitantly elevate said terminal and dispose the latter at the back of the depressed blade, said spring means cooperating to bodily forwardly displace said trigger during retraction of said blade at a time when the latter is bodily above the elevation of said trigger.

30 33. In a stapling machine, the combination of, a pin, a staple supporting trigger having an elongated opening surrounding said pin, reciprocal blade means for actuating said trigger, means comprising a vertical raceway, helicoidal spring means cooperating with said trigger to 35

normally hold the forward portion thereof to overhang said raceway, said trigger on downward displacement thereof compressing said spring means, said forward portion on continued downward displacement of said blade means adapted to be free of the latter, said spring means upon freeing of said forward portion by said blade means automatically bodily rearwardly displacing said trigger and elevating said forward portion at the back of said blade means, said blade means on retraction thereof rising above the elevation of said forward portion, said spring means bodily displacing said trigger forwardly when said blade means is above the elevation of said elevated forward portion.

34. In a stapling machine, the combination of, a base having an anvil, an arm pivotally connected to said base, self elevatable driving means reciprocably guided in said arm and comprising a housing, stroke control means having an opening, a lug carried by said housing and normally disposed at the upper part of said opening, a spring controlled latch having a terminal disposed out of said opening and abutting said lug, said terminal entering said opening at the beginning of the downward stroke of said housing and constituting intervening means to prevent complete retraction of said housing.

35. In a stapling machine, the combination of, a base, an arm pivotally connected to said base, self elevatable driving means reciprocably guided in said arm and comprising a housing, stroke control means having an opening, a lug carried by said housing and normally disposed at the upper part of said opening, a spring controlled latch having a terminal abutting said lug, said terminal entering said opening at the beginning of the downward stroke of said housing and constituting intervening means to prevent complete retraction of said housing, and means actuated by said housing after a complete downward stroke thereof to removably displace said intervening means out of said opening upon the retraction of said housing pursuant to a complete downward stroke of the latter to permit said lug to abut an upper face of said opening.

36. In a stapling machine, the combination of, a base, an arm pivotally connected to said base, self elevatable driving means reciprocably guided in said arm and comprising a housing, stroke control means having an opening, a lug carried by said housing and normally disposed at the upper part of said opening, a spring controlled latch having a terminal abutting said lug, said terminal entering said opening at the beginning of the downward stroke of said housing and constituting intervening means to prevent complete retraction of said housing, a rotatable pawl overhanging said opening, said housing having means for actuating said pawl to displace said intervening means out of said opening upon complete retraction of said housing pursuant to a complete downward stroke of the latter and permit said lug to abut an upper face of said opening.

65 37. In a stapling machine, the combination of, a base, an arm pivotally connected to said base, self elevatable driving means reciprocably guided in said arm and comprising a housing, stroke control means having an opening, a lug carried by said housing and normally disposed at the upper part of said opening, a spring controlled latch having a terminal abutting said lug, said terminal entering said opening at the beginning of the downward stroke of said housing and constituting intervening means to prevent complete re-

traction of said housing, an oscillatable pawl overhanging said opening and comprising spaced fingers, said housing having abutting means to actuate said pawl on the downward stroke thereof to permit one of said fingers to move said intervening means out of said opening and subsequently permit said terminal to be disposed within said opening, said abutting means adapted to actuate said pawl on the upward stroke of said housing to permit another finger of said pawl to displace said terminal out of said opening and allow said lug to abut an upper face of said opening.

38. In a stapling machine, the combination of, a base, an arm pivoted thereto, reciprocable driving means slidably carried by said arm, openings in said driving means, an oscillatable member having projecting means receivable in said openings, an opening for removably receiving a portion of a spring pressed latch member cooperating with a stop lug carried by said driving means, the lug cooperating to limit upward displacement of the driving means, and an opening in said driving means adapted to receive a spring for automatic return of said driving means.

39. In a stapling machine, a core having forwardly spaced portions having inclined surfaces to downwardly direct pieces of staples, an oscillatable trigger having a forward part interposed between said portions, and a rail mounted on said core overhanging a reduced portion of said core and spaced from said trigger.

40. In a stapling machine, a track having spaced forward portions each having an inclined face, the faces defining a gap of decreasing width downwardly, and a trigger pivotally carried by said track and having a forward part disposed in said gap.

41. In a stapling machine, a track comprising a core having spaced forward portions each having an inwardly disposed inclined face, the faces defining a gap of decreasing width downwardly, a trigger having a loose pivotal connection with said core and comprising a forward portion disposed in said gap, and a rail mounted on said core and having a forward end overhanging a reduced part of said core and disposed above the forward portion of said trigger.

42. In a stapling machine, a track comprising a core having an upper reduced portion and spaced forwardly extending projections provided with inclined surfaces to form a fragmentary staple receiving gap of decreasing width downwardly.

43. In a stapling machine, a frame having spaced sides, a rail for supporting staples interposed between said sides and forming therewith a longitudinally disposed channel, and means projecting from said sides and towards corresponding sides of said rail within lower portions of said channel for closely but slidably guiding the sides of said staples in said channel.

44. In a stapling machine, a frame having spaced sides, a rail for supporting staples fixedly interposed between said sides and spaced therefrom, and a rib projecting from each of said sides and towards a corresponding side of said rail to closely but slidably guide said staples.

45. In a stapling machine, a frame having spaced sides, a fixed rail for supporting staples interposed between said sides and defining with the sides of said frame vertically disposed gaps adapted to receive spaced legs of said staples, and a rib extending from each side of said frame towards a corresponding side of said rail to cooperate with the lower portions of said legs.

to closely but slidably guide the latter in said gaps.

46. In a stapling machine, a frame having spaced sides, a fixed rail for supporting staples interposed between said sides and defining with the sides of said frame spaced vertically disposed gaps adapted to receive spaced depending legs of said staples, and ribs extending from the sides of said frame and projecting into said gaps to cooperate with said legs to closely but slidably guide the latter in said gaps.

47. In a stapling machine, a rail for supporting a staple strip, a follower mounted on said rail and including an upstanding and inclined abutment, a saddle removably mounted on said follower and including an opening having a rear wall adapted to frictionally engage said abutment, a spring for urging said follower against the rearward part of said strip, a bearing connected to said spring, and a transversely disposed pin carried by said saddle and rotatably sustained by said bearing whereby upon sudden impact of said saddle against said abutment said bearing and pin permit tilting of said saddle relative to said spring to disengage said saddle from said abutment.

48. In a stapling machine, a frame having spaced sides, a rail for supporting staples interposed between said sides and forming therewith a longitudinally disposed channel, and ribbed means projecting from said sides and towards corresponding sides of said rail to constrict said channel and having substantially vertically disposed surface means spaced from the vertical staple guide faces of said rail for closely but slidably guiding the sides of said staples in said channel.

49. In a stapling machine, a core having forwardly extending spaced projections having inclined surfaces to downwardly direct pieces of staples, a block having a centrally arranged vertical slot, an oscillatable trigger having a forward part interposed between said projections and a terminal part movably disposed in said slot, and a rail mounted on said core and overhanging a reduced portion thereof and having a forward portion mounted on a reduced part of said block.

50. In a stapling machine, a core having forwardly extending spaced projections having inclined surfaces to downwardly direct pieces of staples, a race block abutting said projections and having a slot, a trigger, means carried by said core for pivotally and slidably supporting

said trigger, spring means to normally hold the front terminal of said trigger at the upper part of said slot, and a rail mounted on said core and overhanging a reduced portion thereof and having a forward portion mounted on a reduced part of said block.

51. In a stapling machine, a frame, a core secured to said frame and having forwardly extending spaced projections defining a tapering throat, a block disposed forwardly of said throat and abutting said projections and having a slot in communication with said throat, a trigger, means pivotally and slidably supporting said trigger, spring means cooperating to hold the forward part of said trigger at the upper part of said slot, a channeled shaped member secured to the sides of said frame and defining with said block a vertically disposed staple raceway, said spring means cooperating to urge said trigger to permit said forward part thereof to overhang said raceway, said block having a reduced portion and spaced openings adjacent the latter in communication with said throat, and a rail mounted on said core and having a forward portion overhanging a reduced part of said core and sustained by said reduced portion of said block.

52. In a stapling machine, a frame, a core secured to said frame and having forwardly extending spaced projections defining a tapering throat, a block abutting said projections and having a slot in communication with said throat, a trigger, means pivotally and slidably supporting said trigger, spring means cooperating to hold the forward part of said trigger at the upper part of said slot, a channeled member secured to the sides of said frame and defining with said block a vertically disposed staple raceway, said spring means cooperating to urge said trigger to permit said forward part thereof to overhang said raceway, said block having a reduced portion and spaced openings adjacent the latter and in communication with said throat, and a rail mounted on said core and having a forward portion overhanging a reduced part of said core and sustained by said reduced portion of said block, the openings of said block defining means to permit fragmentary pieces of staples in said raceway to fall in back of said block and into said throat, said block having spaced shute means to direct fragmentary pieces of said staples downwardly relative to said raceway.
